UNITED STATES PATENT OFFICE

148,970

DESIGN FOR A FONT OF KEYBOARD SYMBOLS

Lin Yutang, New York, N. Y.

Application May 18, 1946, Serial No. 129,826

Term of patent 14 years

(Cl. D64—12)

To all whom it may concern:

Be it known that I, Lin Yutang, a citizen of the Republic of China, residing in the city, county, and State of New York, have invented a new, original, and ornamental Design for a Font of Keyboard Symbols, of which the following is a specification, reference being had to the accompanying drawing, forming a part thereof, in which the drawing illustrates face views of a font of keyboard symbols, showing my new design.

I claim:

The ornamental design for a font of keyboard symbols, as shown.

LIN YUTANG.
